(57) **CLAIM**

The ornamental design for a bending machine as shown and described.

DESCRIPTION

1.1 Front, Top Left Perspective

1.2 : Front

1.3 : Back

1.4 : Top

1.5 Back, Top Left Perspective

1.6 : Left

1.7 : Right

2.1 Front, Top Left Perspective

2.2 : Front

2.3 : Back

2.4 : Top

2.5 Back, Top Left Perspective

2.6 : Left

2.7 : Right

Figures **1.1-1.7** are the Front, Top Left Perspective view, Front view, Back view, Top view, Back, Top Left Perspective view, Left view and Right view of the bending machine Design 1 respectively; Figures **2.1-2.7** are the Front, Top Left Perspective view, Front view, Back view, Top view, Back, Top Left Perspective view, Left view and Right view of the bending machine Design 2 respectively.

The broken lines showing of a bending machine are included for the purpose of illustrating environmental structure and forms no part of the claimed design.
